2,042,961

TIE RETAINER

Lucien E. Picolet, Philadelphia, Pa.

Application October 2, 1934, Serial No. 746,493

5 Claims. (Cl. 24—56)

This invention is one of the class of devices which are employed to obviate the tendency of the knot of a tie, more particularly of the widely used "sailor knot" or "four-in-hand tie" to slip below its proper position after it has been worn a short time, and is especially applicable for use with the "turn-down" type of collar.

In the drawing which is appended:

Fig. 1 is an elevation of a collar with the tie in normal position. Fig. 2 is an elevation showing the unsupported tie displaced downward. Fig. 3 shows the tie held in place by the tie-retainer. Fig. 4 is a fragmentary top view with the collar in section showing the position and relation of tie, collar and retainer. Fig. 5 is a plan and Fig. 5a is an elevation of a preferred form of tie-retainer. Fig. 6 is a fragmentary top view with the collar in section showing the position of the tie, collar and retainer of the form shown in Fig. 7. Fig. 7 is a modified form of retainer which is curved to conform to the collar band with the ends bent outward to form radial fins. Fig. 7a is a plan view of Fig. 7. Fig. 8 is a simplified form of retainer in plan and Fig. 8a in elevation.

Normally, the topmost part of the knot, 1, Fig. 1, should come above the collar-button, 2, and close the V formed by the flaps 19 and 20 of the collar. Inevitably, the slight movement to which it is subjected by the wearer causes the knot to slacken and become displaced downward sufficiently to expose the collar-button 2, Fig. 2, despite the often-used scarf-pin 7 to aid in maintaining the tightness of the knot 1.

It will be noticed from an inspection of Figs. 1 and 2, that the knot normally is supported only by the oppositely directed tensions which are applied to the knot at the points 3 and 4 by the narrowed part of the tie which encircles the collar within its fold and enters the knot 1 at those points. Since the equal forces at 3 and 4 which tend to keep the knot 1 in place are only slightly inclined to a perpendicular to the direction of the force which urges the tie downwards, it is evident that the equilibrating restraining forces at 3 and 4 must be much greater than the downward force and entail tensions at 3 and 4 which are too great to be maintained by the friction between the folds of the tie within the knot, and as experience proves, even when aided by the locking action of a stick-pin 7 applied to the depending scarf 5 below the knot 1. It is understood that the band 6, knot 1, and depending scarf 5 are in one piece suitably trimmed as to width.

The device which is designed to overcome the above described difficulties in maintaining the tie in its proper position, and constitutes the subject of this application, is shown in Fig. 5. It consists essentially of a blade-like beam 9 which rests edgewise at the middle of its length upon the shank 18 Fig. 4 of the collar-button 2 through a perforation at that point 8 which is wide at 8' and narrow at the top at 8² while the ends 10 and 11 support the knot 1 by bearing upwards upon the points 3 and 4 of the band 6 at which it enters the knot 1 at opposite sides. The bearing points 10 and 11 are provided with serrations in order to prevent possible slipping. The retainer 9 is shown in place in Figs. 3 and 4 in which are shown the serrated bearing-ends 10 and 11 engaging the band 6 and the point of support 8 resting upon the shank 18 of the collar-button 2. Thus the retainer consists substantially of a thin beam which is loaded at the ends by the contact of the tie-band 6 and supported at the middle by the shank 18 of the collar-button 2, Figs. 3 and 4. It will be evident that the load at the outer ends by the contact of the tie-band 6 holds the retainer down with in the narrow portion 8² of the opening 8 engaging and held in place by the collar button 2. The concave depression 15 which is provided between the serrated ends 10 and 11, Fig. 5 is to permit an easy entrance of the retainer 9 into place between the collar band 16 and the knot 1, Fig. 4 and avoid crowding the knot.

In applying the retainer, the tie is adjusted in the usual manner, the knot being drawn up snugly to the desired position as in Fig. 1. The retainer 9 is then slipped between the collar-band 15 and the knot 1, and pressed upwards until the ends 10 and 11 of the retainer make contact with the tie band 6, and the opening 8 Fig. 5 registers with the collar-button 2, when it is readily pushed inwards to rest on the shank 18, Fig. 4. The band 6, Fig. 3, being held up by the retainer at the ends 10 and 11, Fig. 5 the tie-band 6 cannot assume the position which is shown in Fig. 2 even with a slight loosening of the knot 1.

A modified form of the retainer is shown in Fig. 7. It effects the same object as that shown in Fig. 5, but differs from it in being curved so as to conform to the curve of the collar-band 16 against which it is designed to rest snugly while the extreme ends are bent outwards to form radial fins 12 and 13 which support the tie-band 6. The fragmentary section of Fig. 6

shows the manner in which this form of retainer engages the tie-band 6.

The form of Fig. 8 is similar in general shape to that of Fig. 5 but without serrations 10 and 11 and the reentrant curve 15 between them.

5 I claim:

1. A one-piece necktie retainer comprising a sheet of flat material having an elongated opening through the sheet narrower at the top than at the bottom adapted to pass the head of a collar button, the bottom portion being adapted to pass the end of the collar button and the top portion of the opening being adapted to fit the shank of the collar button, the sheet having upper flat bearing points laterally extending on either side of said opening to receive and support the neck band portion of a necktie whose tied portion is in front of said opening and free from permanent attachment to the retainer whereby the knot is supported and the tie retainer is positioned.

2. A necktie retainer of sheet material having a central portion perforated by an elongated opening which is wide at the bottom for passing the head of a collar button and narrow at the top for engagement with the collar button shank and having wings on either side of the necktie, the upper surface of the wings and central portion forming a substantially straight line from one side to the other side of the retainer and the under surface of the retainer following the general contour of the opening at the central portion at the bottom and sloping upwardly from the central portion to the extremities of the winged portion, whereby central support is provided for the retainer and balanced bearing contact is had with the necktie on either side of the support.

3. A one-piece necktie retainer of sheet ma-

terial having a central portion perforated by an elongated opening which is wide at the bottom for passing the head of a collar button and narrow at the top for engagement with the collar button shank and having wings extending on either side of a necktie knot, the wings engaging a neckband of the tie about a collar, on either side of the knot, the upper surface of the wings and central portion forming a substantially straight line from one side to the other side of the retainer and the under surface of the retainer extending outwardly to the extremities of the winged portions, whereby central support is provided for the retainer and balanced bearing contact is had with the necktie 15 on either side of the support.

4. In a necktie device, a necktie retainer of sheet material perforated with a central opening which is adapted to pass over the head of the collar button and rest upon its shank, the 20 retainer having symmetrical wing portions extending on opposite sides of the opening which provide resting points upon their top limiting surfaces which support the downward pressure of the tie band on either side of the knot, and 25 establish equilibrium between the downward pressure of the tie and the upward pressure of the collar-button.

5. In a necktie device, a necktie retainer of sheet material perforated with a central opening narrower at the top than at the bottom adapted to rest at its top narrower part upon the shank of the collar-button and having wing portions outwardly extending on either side of the opening, upon the top limiting surface of 35 which the necktie band passing around the neck of the wearer is supported.

LUCIEN E. PICOLET.
